US0D1111061S

(12) **United States Design Patent** (10) **Patent No.:** **US D1,111,061 S**
(45) **Date of Patent:** **** Feb. 3, 2026**

(54) **ROUND SIFTER**

(71) Applicant: **MLM Solutions, LLC**, Austin, TX (US)

(72) Inventor: **Michael S. Perez**, Austin, TX (US)

(73) Assignee: **MLM Solutions, LLC**, Austin, TX (US)

(**) Term: **15 Years**

(21) Appl. No.: **29/790,768**

(22) Filed: **Dec. 14, 2021**

(51) **LOC (15) Cl.** **15-03**

(52) **U.S. Cl.**

USPC **D15/28**

(57) **CLAIM**

The ornamental design for a round sifter as shown and described.

DESCRIPTION

FIG. 1 is a top view of a round sifter in accordance with the present disclosure;

FIG. 2 is a bottom view thereof;

FIG. 3 is an isometric view thereof from the top;

FIG. 4 is an isometric view thereof from the bottom;

FIG. 5 is a side view thereof;

FIG. 6 is an exploded isometric view thereof from the top; and,

FIG. 7 is an exploded isometric view thereof from the bottom.

The dashed and broken lines represent structures, features, or environmental subject matter that form no part of the claimed design.

1 Claim, 7 Drawing Sheets
